UNITED STATES PATENT OFFICE

GASPARD D. PILON, OF MONTREAL, QUEBEC, CANADA

FASTENER

Application filed May 13, 1929. Serial No. 362,772.

The present invention relates to novel fastening means and has for its primary object to provide a pivotally adjustable fastener which may be conveniently adjusted to a fastening or a disconnecting position.

A further object of the invention is the provision of a fastening device embodying an elongated member mounted for frictional swinging movement to secure or release an article to a body carrying the fastening member.

Another object of the invention is the provision of a fastener adapted for fastening garments and various other articles.

Still another object of the invention is the provision of a fastener designed to replace the common form of fixed button providing a tapered member which may be adjusted and conveniently inserted through a slit or buttonhole.

Still another object of the invention is the provision of a fastener of the above character which will be simple and durable in construction and convenient in use.

Other objects and advantages of the invention will become apparent as the description progresses.

In the accompanying drawing forming a part of this specification and in which like reference characters are employed to designate corresponding parts throughout the same:

Figure 1 is a perspective view of the fastening member in detached position,

Figure 2 is a top plan view of the fastener in garment securing position,

Figure 3 is a side elevational view of the fastener in garment securing arrangement,

Figure 4 is a similar view showing the fastener disposed in a garment releasing position, and

Figure 5 is a transverse section taken on the line 5—5 of Figure 2.

Referring to the drawing, wherein for the purpose of illustration is shown a preferred embodiment of the invention, the fastening device is shown applied to a garment, as for instance an open front sweater having the overlapping portions 10 and 11, the portion 10 comprising the under for-

ward margin while the portion 11 indicates the exterior portion which overlaps the under portion 10.

The fastening device embodies a body 12 of elongated form tapered from the inner enlarged end 13 to the outer reduced end 14. The outer portion 14 is formed with a gradual lateral taper toward the intermediate section of the body, the medial portion being designed to provide inwardly curved configurations to provide an intermediate reduced weight portion 15. The inner enlarged end 13 is generally in the form of a rounded knob, as clearly shown in Figures 1 and 2. The body is also formed with a longitudinal and vertical undulating curvature so that the intermediate base portion 15 is formed with an upward or outward arch, while the end finger portion 14 is arched downwardly to provide a face contacting section.

Below the enlarged knob portion 15 is formed a right angular, substantially flat bearing member or ear 16, preferably of arcuate substantially semicircular form, having a centrally disposed aperture 17.

The ear portion 16 of the fastener is pivotally connected with the supporting garment fabric 10, or other carrying body, by means of a link 18. The link 18 is preferably formed of rigid metallic material having one section extending through the aperture in the bearing member 16 and the side portions extended through the carrying body and bent over at the inner surface thereof to form a rectangular shaped connecting member, clearly shown in Figure 5. The connecting link 18, may, however, be formed of flexible material such as a thread of durable structure.

In fastening position, the elongated body 12 is slidably extended through a slot or buttonhole 19 formed in the complementary overlapping section 11 of the garment to secure the front divided portions of the garment in closed overlapping positions. The link connection 18 is disposed so as to tightly crush the arcuate edge of the bearing ear 16 against the exterior surface of the

carrying body to permit frictional swinging or pivotal adjustment of the fastener.

In use, to connect the body front portions of a garment, the fastener is swung to an outwardly directed position and the overlapping portion 11 of the garment disposed so that the slit or buttonhole 19 is slidably fitted over the extended fastener member and this portion of the garment is positioned over onto the under portion. The fastener is then swung inwardly so that the outer arched finger portion 14 will press against the outer surface of the overlapping garment material and will hold the same against disconnected movement. This construction will eliminate the difficulty of positioning the apertured portion of the garment over the fastener and will substantially reduce the deterioration of the button hole structure, as is customary in the use of the common form of buttons now employed and which must be forced through the buttonholes. Furthermore, the fastening operation may be effected very quickly and conveniently without damage to the garment.

It is to be understood that the form of my invention herein shown and described is to be taken as a preferred example of the same, and that various changes as to the shape, size, and arrangement of parts may be resorted to without departing from the spirit of the invention or the scope of the subjoined claim.

Having thus described my invention, I claim:

A garment fastener adapted to be permanently secured to a garment, comprising an elongated body portion the middle of which is slightly convex and curved upwardly at one end, an enlargement at the other end of the body the under face of which is in line with the under portion of the other end, a longitudinally disposed ear integral with the enlargement extending downwardly therefrom at right angles and having an aperture therethrough, and a link passed through said aperture and adapted to permanently secure the fastener to one flap of a garment, the fastener furthermore cooperating with a button hole in a corresponding flap of the garment to secure both flaps thereof when the body of the fastener is inserted into the buttonhole.

In witness whereof I have hereunto set my hand.
